DESIGN FOR A MOUNTING BRACKET FOR AN ELECTRICAL FIXTURE

Clyde D. McCann, Des Moines, Iowa

Application November 29, 1946, Serial No. 135,153

Term of patent 14 years

(Cl. D48—4)

To all whom it may concern:

Be it known that I, Clyde D. McCann, a citizen of the United States and a resident of Des Moines, in the county of Polk and State of Iowa, have invented a new, original, and ornamental Design for a Mounting Bracket for an Electrical Fixture, of which the following is a specification, reference being had to the accompanying drawing, forming part thereof, in which:

Fig. 1 is a top plan view of a mounting bracket for an electrical fixture, showing my new design;

Fig. 2 is a rear view;

Fig. 3 is a side view looking toward the left in Fig. 2; and

Fig. 4 is a sectional view on the line 4—4 in Fig. 3.

I claim:

The ornamental design for a mounting bracket for an electrical fixture, substantially as shown.

CLYDE D. McCANN.
